W. W. WELPLEY

GAME APPARATUS

Filed Nov. 9, 1927

INVENTOR,
Walter W. Welsley.
By Martin P. Smith, Atty.

UNITED STATES PATENT OFFICE.

WALTER W. WELPLEY, OF HAWTHORNE, CALIFORNIA, ASSIGNOR OF ONE-HALF TO
H. C. PROULX, OF PASADENA, CALIFORNIA.

GAME APPARATUS.

Application filed November 9, 1927. Serial No. 232,048.

My invention relates to a game apparatus, and has for its principal object the provision of a relatively simple and inexpensive apparatus that may be played or manipulated by 5 one or more players or contestants, and which will afford interesting and amusing entertainment by reason of the fact that the play of the game represents the flights of aeroplanes to different countries or cities of 10 the world.

A further object of my invention is to provide a game apparatus of the character referred to, which has in addition to its entertaining and amusing qualities, the desirable 15 feature of instruction, inasmuch as the apparatus and its play involves some of the primary principles of the attractions of bodies as the result of magnetism.

With the foregoing and other objects in 20 view, my invention consists in certain novel features of construction and arrangement of parts that will hereinafter be more fully described and claimed and illustrated in the accompanying drawing, in which—

Fig. 1 is a perspective view of a game apparatus embodying the principles of my invention.

Fig. 2 is a longitudinal cross section taken on the line 2—2 of Fig. 1.

Fig. 3 is an end view of one of the parts of the apparatus and which is shaped so as to represent an aeroplane.

Referring by numerals to the accompanying drawings, 10 designates the base of the apparatus on which the game is played, said base being preferably constructed of suitable thin material such as cardboard, wood, veneer, sheet metal, or the like, and said base being preferably square or rectangular in 40 form.

The base is supported on a suitable frame work 11, and which latter may include two or more longitudinally disposed members and one or more cross members.

45 Secured in any suitable manner at the rear end of the base 10, is an upwardly projecting rail 12, that extends entirely across said base, and secured in any suitable manner on top of said rail, and preferably spaced at equal 50 distances apart, are a number of ordinary horse shoe magnets 13.

Painted or printed on the front face of the rail 12, and directly beneath the mag-

nets 13, are panels 14 containing the names of different cities or countries. 55

Painted or printed on the upper face of the base 10, directly below and in front of the panels 14, are "spots" or small areas 15 circumscribed by circles and which may be provided with suitable designating numerals 60 or characters, and which spots are adapted to receive markers utilized in keeping score of, the game.

Secured to the sides of the base 10, near the front thereof, are the lower ends of an upright frame comprising vertically disposed side members 16, and an upper cross bar 17, which latter is provided with two or more downwardly bent portions 18. 65

Encircling the cross bar 17, and fitting 70 loosely thereupon, is a loop or ring 19, that is formed integral with or fixed to the upper end of a swinging arm 20, the same carrying at its lower end a magnet 21, preferably of horseshoe shape and the attractive power of 75 which is slightly less than that of the magnets 13.

I prefer to construct the swinging arm 20 from wire or a small rod, although in some instances and particularly where the apparatus is made in larger sizes for outdoor play, this swinging arm may be formed of a cable, cord, or chain. 80

Painted or printed on the surface of the base 10, between the members 16 of the upright frame, are spots or marked areas 22, that are preferably arranged in longitudinal alignment with the spots 15 and the magnets 13, and which spots 22 serve as points to position the aeroplane representing members 90 that are utilized in the play of the game. 85

The game pieces, one of which is illustrated in front elevation in Fig. 3, are preferably formed from soft iron, and they are shaped to represent an aeroplane. Each game piece 95 consists of a horizontally disposed plate 23, that represents the wings of a plane, a downwardly and rearwardly projecting portion 24, that represents the fuselage of a plane, and projecting laterally from the forward portion of the member 24 are short horizontally disposed plates 25, that serve to support the game piece in upright position on the plane field. 100

In the play of my improved game, the 105 game piece represents an aeroplane as po-

sitioned on one of the spots or areas 22, and the player moves the swinging arm 20 along the top members 17 of the upright frame until said swinging arm is in substantial alignment with the game piece, and with the fingers of the hand engaging the magnet 21 the arm is drawn forwardly and upwardly until it occupies an angular position as illustrated in Fig. 1. The magnet is now released, and through gravity said magnet and the arm 21 will swing outwardly, thence rearwardly and upwardly describing an arc having the member 17 as its axis. If the arm is manipulated so as to swing directly over the game piece positioned on the plane field, the magnet 21 will, as it passes over the game piece, attract and pick up the same as a result of the attractive powers of the magnet, for metals such as soft iron, and if the game piece is so picked up it will be carried with the magnet rearwardly and upwardly as shown by dotted lines in Fig. 2.

In the event that the arm is properly manipulated so that the magnet 21 passes directly over one of the magnets 13, the latter will, by reason of its greater attractive power than magnet 21, draw the game piece from said last mentioned magnet and said game piece will be transferred to said magnet 13, and thus the player who successfully manipulates the swinging arm 20 and magnet 21, makes, according to the rules of the game, a successful "flight", and scores a point in the game.

During the play of the game, the loop 19 may be positioned in any one of the depressions 18, the latter serving as a bearing for the loop during the swinging action of the magnet carrying member 20, or the loop 19 may be positioned at any point on the cross bar 17 at the top of the upright frame.

The directions for the play of the game may be printed on the base 10, between the spots or areas 15 and 22.

A game apparatus of my improved construction is comparatively simple, may be readily manipulated, and affords a pleasing, entertaining and instructive amusement, particularly for children.

The form of the game apparatus herein illustrated is particularly designed for indoor play, but practically the same apparatus in larger form may be constructed and employed for outdoor play, in which latter event the distance of the flights will of course be much greater, and consequently the manipulation of the swinging member that carries the magnet 21 will require greater skill in making successful "flights".

It will be understood that minor changes in the size, form and construction of the various parts of my improved game apparatus may be made and substituted for those here-

in shown and described without departing from the spirit of my invention, the scope of which is set forth in the appended claims.

I claim as my invention:

1. In a game apparatus, a permanent magnet suspended so as to swing through a vertical arc, a relatively fixed permanent magnet positioned adjacent to the path of movement of the swinging magnet, and a game piece that is adapted to be attracted by said magnets.

2. In a game apparatus, a permanent magnet suspended so as to swing through a vertical arc, a relatively fixed permanent magnet positioned adjacent to the path of movement of the swinging magnet, the attractive power of the relatively fixed magnet being greater than that of the swinging magnet, and a game piece that is adapted to be attracted by said magnets.

3. In a game apparatus, a permanent magnet mounted to swing through a vertical arc, a relatively fixed permanent magnet positioned adjacent to the path of travel of the swinging magnet, and a game piece of metal that is shaped to represent an aeroplane and which game piece is adapted to be attracted by said magnets.

4. In a game apparatus, a pair of magnets, one of which is mounted for swinging movement relative to the other, the swinging magnet having less attractive power than the other magnet, and an aeroplane representing game piece adapted to be attracted and picked up by the swinging magnet and transferred to the stationary magnet.

5. In a game apparatus, a playing board, an upright frame thereon, a permanent magnet suspended for swinging movement upon said frame, a series of permanent magnets arranged on said playing board, and a game piece that is adapted to be attracted by said magnets.

6. In a game apparatus, a playing board, an upright frame positioned thereon, a permanent magnet suspended for swinging movement from the upper portion of said frame, a series of permanent magnets mounted on the rear portion of the frame, the attractive power of which last mentioned magnets is greater than that of the swinging magnet, and a game piece adapted to be attracted by said magnets.

7. In a game apparatus, a playing board, a member supported above said playing board, a permanent magnet suspended for swinging movement upon the said member, a series of permanent magnets mounted on the rear portion of the playing board, and an aeroplane representing game piece adapted to be attracted by said magnets.

In testimony whereof I affix my signature.

WALTER W. WELPLEY.
